CLAIM

The ornamental design for a headlight assembly as shown and described.

DESCRIPTION

FIG. 1 is a perspective view taken from a front, left side of a headlight assembly according to our design;

FIG. 2 is a perspective view taken from a front, right side thereof;

FIG. 3 is a perspective view taken from a rear, left side thereof;

FIG. 4 is a perspective view taken from a rear, right side thereof;

FIG. 5 is a front elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a rear elevation view thereof;

FIG. 11 is a close-up view of section 11 of FIG. 1;

FIG. 12 is a close-up view of section 12 of FIG. 2;

FIG. 13 is a close-up view of section 13 of FIG. 3;

FIG. 14 is a close-up view of section 14 of FIG. 4;

FIG. 15 is a close-up view of section 15 of FIG. 5;

FIG. 16 is a close-up view of section 16 of FIG. 6;

FIG. 17 is a close-up view of section 17 of FIG. 7; and,

FIG. 18 is a close-up view of section 18 of FIG. 8.

Throughout the Figures, where shown, the dashed lines showing portions of the snowmobile form no part of the claimed design.

1 Claim, 18 Drawing Sheets
